MATERIAL FEEDING APPARATUS

Frank Martindell, Western Springs, Ill., assignor
to Western Electric Company, Incorporated,
New York, N. Y., a corporation of New York

Application July 10, 1940, Serial No. 344,755

7 Claims. (Cl. 271—2.5)

This invention relates to material feeding apparatus and more particularly to apparatus for feeding electrical terminals in continuous strip form and locating the leading terminal at a predetermined position.

The invention is particularly applicable to intermittently feeding and locating a leading terminal of a continuous strip of interconnected terminals. Each terminal is provided with a narrow portion and an apertured head portion which provide regularly spaced indentations and shoulders, the terminals being fed to a predetermined position in a processing machine where the leading terminal is severed from the strip and attached to a relay spool head, or otherwise handled.

An object of this invention is the provision of an improved apparatus for rapidly and efficiently feeding, accurately locating and applying strip terminals to a relay spool head.

In one embodiment of the invention, an apparatus is provided for feeding and accurately locating a pair of terminals in the above form for attachment to relay spool heads by means of a standard eyelet setting machine. The apparatus comprises a feeding apparatus having sets, one for each strip, of spring pressed pivotal and reciprocable feeding fingers and an intermediate pivotal friction block carried by a slide member. Cooperating with the feeding fingers and arranged forward thereof is a pivotal spring pressed member having stop abutments for accurately locating the leading terminals, the member carrying a shearing blade which cooperates with a stationary shearing blade to sever the terminals. The slide and spring pressed member are operated in timed relation with the riveting head and a rivet feeding means during each operating cycle of the machine to cause the feeding fingers of each set, which are normally behind trailing shoulders of the strip, to over feed the terminal head portion, which follows the leading terminal, past the abutments of the spring pressed member, under which the shoulders are cammed. Upon the shoulders being advanced past the abutments they are spring moved into the path of the abutments and during the return stroke of the slide member the strip is drawn back by the frictional grip of the friction block thereon until the trailing shoulders of the head portion which were overfed engage the abutments and thus the head portion of the leading terminal is accurately located. During the remaining portion of the return stroke of the slide member the strip is held stationary and the pivotal feeding fingers on the slide are cammed upwardly and ride over following shoul-

ders and finally spring into position behind these shoulders ready for the next strip feeding movement.

Other objects and advantages of the invention will more fully appear from the following detailed description, taken in connection with the accompanying drawings, in which

Fig. 1 is a diagrammatic side view showing the general arrangement of the strip material feeding and locating apparatus embodying the invention in association with an eyelet setting machine to which it is operatively connected and which is fragmentarily shown;

Fig. 2 is an enlarged end view, partly in section, taken on the line 2—2 of Fig. 1;

Fig. 3 is a vertical sectional view taken on the line 3—3 of Fig. 2 showing the position of the feeding fingers relative to the trailing strip shoulders at the completion of a feeding movement and before the strip is drawn backwards;

Fig. 4 is a fragmentary plan sectional view taken on the line 4—4 of Fig. 3;

Fig. 5 is an enlarged vertical sectional view taken on the line 5—5 of Fig. 1;

Fig. 6 is a vertical sectional view taken on the line 6—6 of Fig. 5 showing the trailing strip shoulders drawn back against the abutments on the spring pressed member, portions of the eyelet setting machine being shown diagrammatically;

Fig. 7 is a fragmentary view similar to Fig. 6 showing the position of the spring pressed member, having the stop abutments, during the feeding of the strips;

Fig. 8 is a fragmentary vertical sectional view taken on the line 8—8 of Fig. 6;

Fig. 9 is a bottom plan view taken on the line 9—9 of Fig. 6;

Fig. 10 is a plan view of the terminals after being attached to a relay spool head, and

Fig. 11 is a side view thereof.

One embodiment of the strip material feeding and locating and severing apparatus of this invention is shown in the drawings applied to the intermittent simultaneous feeding of a pair of continuous strips 10 (Figs. 1, 2 and 9) of interconnected electrical terminals 11 (Figs. 6 and 11) to accurately present the leading terminals for attachment to a predeterminedly positioned relay spool head 12. In the present disclosure the terminals 11 after being accurately located (Fig. 6) are severed from the strips and then attached to the spool heads 12 by eyelets 13 which are automatically entered into aligned apertures 14 in head portions 15 of the terminals and spool head 55 and then set or riveted. The free ends of the

terminals 11 which are narrow relative to the head portions 15 are bent upwardly at right angles to the head portions before being attached to the spool head, as indicated at 16 (Figs. 6 and 11). Thus, at regularly spaced points along the strip 10 where the terminal head portions 15 meet the narrow portions of the terminals 11 there are provided sets of aligned pairs of shoulders 17, the trailing pairs of shoulders of each set being used in the feeding of and the locating of the leading terminal.

The above mentioned operations are effected in timed relation and during each operating cycle of a usual standard eyelet feeding and setting machine, the apparatus for effecting the various operations receiving motion from elements of the eyelet machine. For the sake of simplicity only such portions of the eyelet setting machine have been shown which are necessary to an understanding of the present invention in one particular application thereof.

Referring to the drawings, particularly to Fig. 1, 20 is a bed plate or table upon which the strip feeding apparatus and combined strip locating and severing apparatus, indicated in general at 21 and 22, respectively, are mounted. Also, carried upon the bed plate 20 are spools 23, one of which is shown, upon which are wound the continuous strips 10 of interconnected terminals 11.

The feeding apparatus 21 comprises a pair of spaced vertical standards 24 (Figs. 1, 2 and 3) secured to the table 20 and having aligned slideways 27 formed in their inner opposed surfaces. Carried between the standards 24 is a slide 28 having tongues 29 slidable in the slideways 27. The slide 28 at its left end (Figs. 3 and 4), is provided with spaced longitudinally extending slots 30. Pivoted upon the slide 28 at 31 in each of the slots 30 is a pair of spaced strip feeding fingers 34 and an intermediate friction block 35 (Figs. 2 and 4) one for each strip 10 of terminals. The details of the finger and friction block of each set are identical and, therefore, the following description applies to each set. The lower edges of the fingers and block are relieved at their right ends, as indicated at 36 (Fig. 3) to provide clearance space between the strip 10 and the fingers when the latter are rocked clockwise about their pivot 31. At their left ends lower extending edge portions 37 (Fig. 3) of the fingers 34 normally rest upon the upper surface of a bottom plate 38 secured to the slide 28 by screws 41 (Fig. 2). The pivotal fingers 34 and block 35 normally are pressed downwardly by the action of a leaf spring 42 bearing thereon and secured to the slide 28. The fingers are of such a thickness and so spaced apart by the friction block 35 that they freely engage the right hand or trailing pair of aligned shoulders 17 of the terminal head portions 15 during the feeding of the strip 10. The strip 10 is confined and guided during its movement in a slot 43 formed in the bottom surface of the slide 28 in cooperation with the upper surface of the bottom plate 38, the slot being of suitable width to permit a free movement of the finger portions 37 thereinto. At their right ends the lower edges of the finger portions 37 are inclined upwardly to provide cam faces 44 (Fig. 3), which during a return movement of the slide 28 toward the right after a strip feeding movement cause the spring pressed fingers to move clockwise about their pivot 31 as the fingers ride over following strip shoulders 17, the fingers finally moving downwardly into position behind the shoulders ready for the next

strip feeding movement. The lower edge of the friction block 35 except for its relieved right end is in constant engagement with the central portion of the upper surface of the strip 10 and during the return movement of the slide 28 its frictional engagement with the strip is such that it serves to draw the strip backward a predetermined distance until over-fed trailing head shoulders 17 thereof engage stop abutments, which will be described presently.

Secured to the slide 28 in a slot 45 (Fig. 2) formed in the upper surface of the slide intermediate the sets of feeding fingers 34 and friction blocks 35 is a rack 48 which meshes with a pinion 49 formed on a shaft 50 journaled at opposite ends in the standards 24. Fixed to the shaft 50 at its right end (Fig. 2) is a pinion 51. Pivoted upon the shaft 50 adjacent the pinion 51 is a rack holder and guide 52. Meshing with the pinion 51 is a rack 55 which is supported and guided in the holder and guide 52, the rack being operatively connected (Fig. 1) to an actuating arm 56 attached to and receiving motion from an eyelet feed chute 57 of the eyelet feeding and setting machine, the feed chute being oscillated during each operating cycle of the machine.

The combined strip locating and severing apparatus 22 (Figs. 1, and 5 to 9, inclusive) which is arranged at the left of the feeding apparatus 21 (Fig. 1) comprises a pair of standards 60, secured to the table 20, between which is freely mounted a pivotal member 61 having integral shafts 62 at opposite sides which are journaled in bearings 63 formed in the standards 60 and the table 20. The right hand shaft 62 has secured thereto a lever 64 carrying a roller 67 at its free end (Fig. 1). The lever 64 is rocked in a counterclockwise direction by a cam 68 carried by a reciprocating riveting head 69 (Figs. 1 and 6), the cam engaging the roller 67 at a predetermined point in the downward movement of the riveting head. Formed upon the lower surface of the pivotal member 61 at its left end are depending spaced sets of stop abutments 70 having stop faces 71 against which the trailing head shoulders 17 on the strip 10 are abutted (Figs. 6 and 9) when the strip is drawn back after being over-fed. The abutments 70 are spaced apart a suitable distance to provide a slot 72 for receiving the narrow portions of the strip after the feeding movement thereof. The slot 72 is in alignment with the strip confining and guiding slot 43 of the slide 28, the depth of the slots 43 and 72 being substantially equal to the thickness of the strip 10. At their right ends the lower surfaces of the abutments 70 are inclined upwardly to provide cam faces 74 (Figs. 6 and 9) which during the feeding of the strip 10 by the fingers 34 toward the left cause the strip 10 to be deflected downwardly due to the head shoulders on the strip riding upon the cam faces 74 of the abutments 70, as shown in Fig. 7.

A two armed leaf spring 75 secured in a slot 76 formed in the upper surface of the table 20 and secured by screws 77 normally urges the pivotal member 61 in a clockwise direction. A stop bar 78 spanning and secured upon the standards 60 limits the clockwise movement of the member 61. At its right end the lower surface of the member 61 is relieved at 81 and the strip 10 is guided between the opposed upper surface of the spring 75 and the lower surface of the member 61, the spring arms pressing the strips individually against the member. At its

left end the pivotal member 61 is undercut and suitably secured thereto is a shearing blade 82 with its lower surface and cutting edge 83 in the plane of the lower surface of the member 61. Cooperating with the movable shearing blade 82 is a stationary shearing blade 84 suitably secured and supported in a notch in the table 20. Strip guiding notches 85 are provided in the shearing blade 84, one of which is indicated in Fig. 6 and the shearing edge is indicated at 83. The width of the notch 85 is such that the terminal head portions 15 may freely pass therethrough.

At the left end of the table 20 (Figs. 1 and 6) is a yieldably mounted work support 89 having its upper surface normally spaced from an undercut bottom surface of the stationary shearing blade 84. Secured in apertures in the work support 89 are a pair of anvil and eyelet upsetting dies 90, only one of which is shown in the drawings. The relay spool head 12 is carried upon the support 89 during the attaching of the terminals 11 thereto and in the present disclosure the head 12 is manually placed on the support and guided into predetermined position by vertical walls 91, reduced upper ends of the upsetting dies 90 being entered in the apertures 14 of the spool head. The work support 89 is moved downwardly in the attaching of the terminals 11 to the head 12 during the upsetting of the eyelets 13 by the riveting head 69 and the dies 90 and moves upwardly to its normal position as the riveting head moves upwardly. Since yieldable work supports are well known in the art a more detailed description and disclosure thereof is not believed necessary to an understanding of this invention. Disposed above and axially aligned with the upsetting dies 90 are a pair of eyelet pickup fingers 92 which are yieldably mounted in the reciprocating riveting head 69 which has formed in its bottom surface, surrounding the fingers, die formations 93 which cooperate with the dies 90 to upset and clinch the eyelets 13 in attaching the terminals 11 to the spool head 12. In the continued downward movement of the riveting head 69 after the fingers 92 engage the reduced upper ends of the dies 90 the fingers yield and recede into the riveting head 69, as clearly shown in broken outline in Fig. 6. Cooperating vertical opposed spaced surfaces 96 and 97 of the riveting head 69 and shearing blade 84, respectively, serve to bend upwardly, as indicated at 16 (Figs. 6 and 11), the narrow ends of the terminals 11 after the terminals are severed from the strips 10. It will be understood that the descending fingers 92 had previously picked up the eyelets 13 from the feed chute (not shown) and thereafter thrust them into the apertures 14 of the accurately located leading terminals 11 of the strips. As the severed terminals 11 are carried downwardly, the extending narrow ends thereof are bent upwardly between the spaced forming surfaces 96 and 97.

In the operation of the apparatus above described and beginning the cycle of operation with the various elements of the eyelet setting machine positioned as shown in Figs. 1 and 6, the operation is as follows:

As shown, the fingers 92 on the descending riveting head 69 have just picked up the eyelets 13 from the feed chute 57 which in the meantime has been oscillated in a clockwise direction or to the left (Figs. 1 and 6) during which movement the eyelets were stripped from the

chute and simultaneously therewith the overfed strips 10 were drawn back to the position shown in Figs. 1, 6 and 9.

In the above referred to clockwise oscillation 5 of the feed chute 57 the attached actuating arm 56 likewise moves and through the rack 55, pinions 51 and 49 and rack 48 the slide 28 of the strip feeding mechanism 31 is moved towards the right, as viewed in Fig. 3. During this 10 movement of the slide 28 the spring pressed blocks 35, frictionally engaging the strips 10, carry the strips backward to engage the overfed trailing head shoulders 17 thereon with the stop faces 71 of the abutments 70 (Figs. 6 and 9). In the continued movement to the left of the feed chute 57 after the head shoulders 17 are abutting the stop faces 71 the friction blocks 35 slide upon the stationary strips 10 and the spring pressed pivotal feeding fingers 34 due to 15 their cam faces 44 ride up and over the following head shoulders 17 and then are pressed downwardly to carry the leading edge of the portions 37 thereof into feeding position behind the shoulders 17. With the strips 10 thus positioned the trailing shoulders 17 of the terminal heads 15 immediately following the leading terminals 11 are abutting the stop faces 71 of the abutments 70 (Figs. 6 and 9) and thus the apertured heads of the leading terminals are accurately located relative to the eyelet pickup fingers 92 and the spool head 12 which is positioned on the support 89 of the table 20. The descending fingers 92 with the picked up eyelets are next thrust into the aligned apertures 14 of the terminal heads 15. Immediately thereafter as the riveting head 69 continues its descent the cam 68 carried thereby engages the roller 67 on the lever 64 and rocks the latter in a counterclockwise direction, thus actuating 20 the spring pressed pivotal member 61 in a similar direction and by means of the shearing blade 82 carried by the member and the cooperating stationary shearing blade 84 the leading terminals 11 are sheared from the strips 10. In the 25 continuing descent of the riveting head 69 the fingers 92 engage the upper reduced ends of the dies 90 and recede into the riveting head. As the lower end of the riveting head moves by the shearing blade 84 the terminals 11 on the fingers 92 are bent upwardly by the cooperating spaced surfaces 96 and 97 of the riveting head and the stationary shearing blade, respectively. This point in the descent of the riveting head 69 is shown in broken outline in Fig. 6. As the riveting head 69 reaches its lowermost position 30 the eyelets are inserted in the apertures 14 of the spool head and the die formations 93 cooperate with the dies 90 to upset and clinch the eyelets 13, thus attaching the terminals 11 to the spool head 12.

The riveting head 69 now moves upwardly, the operator removing the assembled spool head and terminals and positioning another spool head on the extension 89. As the head 69 rises the spring 35 pressed pivotal member 61 carrying the shearing blade 82 is returned to its normal position against the stop bar 78. Upon the riveting head 69 reaching its uppermost position it begins to move down and at a predetermined point in this movement 40 the chute 57 is oscillated in a counterclockwise direction or to the right (Figs. 1 and 6) and by means of the actuating arm 56, rack 55, pinions 51 and 49 and rack 48 the strip feeding slide 28 is moved towards the left, as viewed in Fig. 3. Thus, the feeding fingers 34, previously moved

into position behind the terminal head shoulders 17 advance the strips 10, the advance movement being such that the forward edges of the strips which were left in line with the shearing edge 83 of the movable blade 82 after the previous shearing operation are first over-fed to the dotted outline position (Fig. 6) and subsequently are drawn back to the full line position, as previously described. During the advance of the strips 10 by the feeding fingers 34 the terminal head shoulders 17 as they pass between the upper surface of the spring 75 and the bottom surface of the pivotal member 61 (Fig. 6) are deflected downwardly as they ride upon the cam faces 74 of the abutments 70, as shown in Fig. 7. Upon the trailing head shoulders 17 being advanced past the stop faces 71 of the abutments 70 the two armed spring 75 acts to press the strips upwardly and the narrow portions of the terminals are entered in the slots 72. The eyelet chute 57 moves to the right until the eyelets 13 carried at its end are axially aligned with the descending pickup fingers 92 which immediately are thrust thereinto and the eyelet chute then moves to the left, the eyelets being stripped therefrom as the fingers continue their downward movement. Simultaneously with the stripping of the eyelets from the chute 57 by the fingers 92, as the chute moves to the left, the over-fed strips 10 are drawn towards the right (Figs. 3 and 6), in the manner previously described, to abut the trailing shoulders 17 of the terminal heads 15, immediately following the leading terminals, against the stop faces 71 of the abutments 70. The apertures 14 in the leading terminal heads 15 are now accurately located to receive the descending fingers 92 and the eyelets 13, as shown in Fig. 6, and at which point this cycle of operation of the strip feeding and locating mechanism commenced.

From the foregoing description, it will be evident that during each operating cycle of the eyelet setting machine with which the strip feeding apparatus and combined locating and severing apparatus of this invention are operatively connected the two continuous strips 10 of interconnected terminals 11 will be intermittently drawn from the supplies 23 and over-fed such a distance that the trailing head shoulders 17 of the terminals following the leading terminals will lie in advance of the stop faces 71, the forward ends of the strips then being drawn backward by the friction blocks 35 until the head shoulders abut the stop faces, thus accurately locating the leading terminals which are then severed, formed and finally attached to the spool head 12 by the eyelets 13.

While the invention has been described with reference to a particular embodiment thereof for feeding and locating strips of interconnected terminals having regularly spaced shouldered head portions for attachment to a spool head by an eyelet setting machine, it will be understood that it may be embodied in various forms, and is capable of other applications limited only by the scope of the appended claims.

What is claimed is:

1. In an apparatus for feeding strip material having spaced projections along opposite sides to a predetermined position, a reciprocatory carriage, means movably carried thereon engaging the material including material feeding members adapted to engage said projections for feeding the material in one direction beyond the predetermined position and to idly ride by and move into feeding relation with the following projec-

tions in a reverse movement of said carriage, said material engaging means including a friction member engaging the material intermediate the feeding members and effective during said reverse movement of said carriage to return the material to its predetermined position, and stops engaged by said projections upon the material reaching its predetermined position.

2. In an apparatus for feeding strip material having spaced projections along opposite sides, said apparatus accurately locating the leading end of the strip material, a reciprocatory carriage, strip material feeding members movably carried thereon adapted to engage said projections for over-feeding the material during movement of said carriage in one direction and to idly ride by and move into feeding relation with following projections in a reverse movement of said carriage, abutments arranged forward of said carriage past which trailing faces of the projections move during the over-feeding of the material, a member cooperating with said abutments effective to move the material into the plane of the abutments after movement thereof, and an element carried by said carriage frictionally engaging the material and during said reverse movement of the carriage moving the projections into engagement with the abutments to accurately locate the leading end of the material.

3. In an apparatus for feeding strip material having spaced projections along opposite sides, said apparatus accurately locating the leading end of the strip material, a reciprocatory carriage, strip material feeding members pivotally carried thereby adapted to engage said projections for over-feeding the material during movement of said carriage in one direction and to idly ride by and move into feeding relation with following projections in a reverse movement of said carriage, abutments arranged forward of said carriage past which trailing faces of the projections move during the over-feeding of the material, a member cooperating with said abutments effective to move the material into the plane of the abutments after movement of said trailing faces therewith, an element pivotally carried by said carriage arranged between said feeding members and frictionally engaging the material between said projections and during said reverse movement of the carriage, moving the projections into engagement with the abutments to accurately locate the leading end of the material, and means effective to constantly press said pivotal feeding members and element toward the material.

4. In an apparatus for feeding strip material having spaced projections along opposite sides, said apparatus accurately locating the leading end of the strip material, a reciprocatory carriage, strip material feeding members pivotally carried thereby having extensions on their lower edges adapted to enter between and engage said projections at opposite sides of the material for over-feeding the same during movement of said carriage in one direction, said lower edges of the feeding members having inclined portions extending from said extensions toward the upper plane of the projections for causing said feeding members to idly ride over and move down into feeding relation with following projections in a reverse movement of said carriage, abutments arranged forward of said carriage past which trailing faces of the projections move during the over-feeding of the material, a member cooperat-

ing with said abutments effective to move the material into the plane of the abutments after movement therepast, an element pivotally carried by said carriage frictionally engaging the material and during said reverse movement of the carriage moving the projections into engagement with the abutments, and resilient means constantly pressing said pivotal feeding members and elements toward the material.

5. In an apparatus for feeding strip material having spaced projections along opposite sides, said apparatus accurately locating the leading end thereof, reciprocatory means engaging said projections for over feeding the leading end of the strip material during movement thereof in one direction, a friction member engaging the material intermediate said feeding means, movable with said reciprocatory means and effective during a portion of a reverse movement thereof to carry the material therewith, and means including a member arranged forward of said feeding means adapted to support and guide the material in said movements, said member having spaced stop faces on its forward end against which trailing faces of the projection on the material are abutted during said portion of the reverse movement of the feeding means to accurately locate the leading end of the material.

6. In an apparatus for feeding strip material having spaced projections along opposite sides, said apparatus accurately locating the leading end thereof, a reciprocatory carriage, strip material feeding members movable thereon adapted to engage said projections for over feeding the leading end of the material during movement of said carriage in one direction and to idly ride by and move into feeding relation with following projections in a reverse movement of the carriage, means carried by said carriage effective during a portion of the reverse movement thereof to carry the material therewith, a member arranged forward of said carriage having depend-

ing spaced portions providing a channel therebetween for receiving the portion of the material between successive projections and having stop faces at their forward ends, the lower faces of said depending spaced portions having inclined portions upon which the projections slide for deflecting the moving material out of the plane of the channel, and a resilient member forming a bottom wall for said channel upon which the material slides effective when trailing faces of the projections move past said stop faces to move the material into the plane of the channel, said trailing faces of the projections being abutted against said stop faces during said reverse movement of said carriage to accurately locate the leading end of the material.

7. In an apparatus for feeding strip material having spaced projections along opposite sides, said apparatus accurately locating the leading end thereof, a reciprocatory carriage, strip material feeding members movable thereon adapted to engage said projections for over-feeding the material during movement of said carriage in one direction and to idly ride by and move into feeding relation with following projections in a reverse movement of said carriage, means carried by said carriage effective during a portion of said reverse movement thereof to carry the material therewith, a member arranged forward of said carriage adapted to support and guide the material in said movements, said member having spaced stop faces on its forward end against which trailing faces of the projections on the material are abutted during said portion of the reverse movement of the carriage to accurately locate the leading end of the material, and a resilient member associated with said member and upon which the material slides for moving the material into the plane of the stop faces after movement of said trailing faces therepast.

FRANK MARTINDELL.
